[57] CLAIM

The ornamental design for a modular unit for cabinet,
bench or the like, substantially as shown.

DESCRIPTION

FIG. 1 is a perspective view of a modular unit for cabinet,
bench or the like, showing my new design;

FIG. 2 is a front elevational view thereof;

FIG. 3 is a left side elevational view thereof;

FIG. 4 is a top plan view thereof;

FIG. 5 is a right side elevational view thereof;

FIG. 6 is a rear elevational view thereof; and

FIG. 7 is a bottom plan view thereof.

*FIG. 1**FIG. 3**FIG. 2*FIG. 4

FIG. 5

FIG. 6

FIG. 7
